UNITED STATES PATENT OFFICE

DANIEL W. WIGGIN, OF YARMOUTH, MAINE, ASSIGNOR TO THE ABBOTT COMPANY, OF YARMOUTH, MAINE, A CORPORATION OF MAINE

MOCCASIN

Application filed September 24, 1930. Serial No. 484,036.

My present invention relates to an improvement in moccasins of the so-called true moccasin type, but one in which certain improved features have been added, so that while preserving the advantages of the true moccasin I attain certain additional advantages, notably that of increased strength and waterproofness where the moccasin is to carry a wear sole on the tread portion of its vamp. In such moccasins as are provided with a wear sole, even though the vamp is tight and in itself waterproof, there is always a tendency to open up at the seam between vamp and toe piece and permit leakage. Furthermore, in wet or in snow there is apt to be a penetration between the tread of the vamp and the sole so that snow or moisture is held in contact with the tread of the vamp which will be eventually wet through or rotted.

In my present invention I provide an extra protection for the seam between toe piece and vamp and by the same means provide for a tight connection with the sole so that no water or snow can enter between the sole and tread of the vamp.

As illustrative of my invention I have shown in the accompanying drawing a characteristic embodiment. In the drawing: 30 Fig. 1 is a general view of a moccasin of the type carrying sole and heel, but this should be understood to be merely as illustrative and in no way limiting, and

Fig. 2 is a transverse section.

In the structure shown I have indicated at 1 a vamp of usual construction and at 2 the usual toe piece. This toe piece, however, is continued as at 3 to form a lateral member which is stitched as at 4 to a sole 5. The 40 vamp and toe piece members 1 and 2 are seamed in the usual manner as at 6, but it will be noted that instead of having a free edge as in previous seams, the seam is completely closed by the continuance of the toe 45 piece area 3 which continues down to the sole to which it is tightly stitched, thus making a waterproof joint at the side of the moccasin.

This construction gives a moccasin not 50 only with a perfectly tight upper seam be-

tween the vamp and toe, but also an additional tight seam at the edge of the sole and in addition provides an extra protective layer along the edge of the foot, thus protecting the toes and giving an extra thickness of material which increases the waterproofness and the wear along area particularly exposed to contact in walking. The toe piece extensions 3 may be cemented to the sides of the vamp 1 and also the edge of the vamp at the seam 6. Also, if desired, the tread of the vamp 1 may be cemented or otherwise fastened to the sole 5.

Such moccasins may be variously designed and may be assembled with or without cement between the exterior portion 4 of the toe piece and the vamp 1. All such changes and modifications are to be considered within the concept of my invention as they will be apparent from the disclosure herein to those skilled in the manufacture of moccasins or moccasin like structures. It will also be understood that while I have shown and particularly described a moccasin having an external wear sole or tap and as an illustrative structure of special advantage, that the moccasin might be made without a sole or have its sole attached in some other manner, the important feature being that the edge of the extensions of the toe piece be brought down and tightly secured by cement or stitching or both adjacent the bottom portion of the vamp.

As shown in the drawing, an intermediate sole 7 is shown as stitched to the vamp, but as above stated the sole or number of soles or type of heel may be varied without departing from the spirit of my invention.

What I therefore claim and desire to secure by Letters Patent is:—

1. A moccasin comprising a vamp, an upper member including a toe area and integral lateral areas extending therefrom, the lateral areas overlying the sides of the vamp, a seam joining the upper member at the junction of its toe and lateral areas with the edge of the vamp, a sole beneath the tread of the vamp, the lateral portions of the upper member being united to said sole at the edges thereof.
2. A moccasin comprising a vamp and an

upper member including a toe area and lateral areas extending therefrom and overlying the sides of the vamp and folded over the edge of the vamp and seamed thereto, a sole beneath the tread of the vamp, the lateral portions of the upper member being united to said sole at the edges.

3. A moccasin comprising a vamp and an upper member including a toe area and lateral areas extending therefrom and overlying the sides of the vamp and folded over the edge of the vamp and seamed thereto, a sole beneath the tread of the vamp, the lateral portions of the upper member being united to said sole at the edges thereof to form a tight joint and cemented to the sides of the vamp and to the edge thereof at said seam.

4. A moccasin including a toe piece and vamp and having a seam in which the toe piece is folded over the edge of the vamp and is held thereto by stitches passing through opposite sides of the fold of the toe piece through the edge of the vamp therebetween, said toe piece extending down the sides of the vamp, and a sole beneath the tread of the vamp, the margins of the toe piece extending being stitched to the edges of said sole.

5. A moccasin comprising a vamp, an upper member including a toe area having lateral areas extending therefrom, the lateral areas overlying the sides of the vamp, said upper member at the junction of its toe and lateral areas being folded to embrace the upper edge of the vamp, a seam joining the fold of the upper member with the upper edge of the vamp, and a sole beneath the tread of the vamp, the lower edges of the lateral areas of the upper member being united with the sole.

In testimony whereof I affix my signature.

DANIEL W. WIGGIN.
